CLAIM

The ornamental design for a case for an electronic device, as shown and described.

DESCRIPTION

FIG. 1 is an isometric view of a case for an electronic device showing my new design.

FIG. 2 is another isometric view of the case of FIG. 1.

FIG. 3 is a front view of the case of FIG. 1.

FIG. 4 is a rear view of the case of FIG. 1.

FIG. 5 is a left side view of the case of FIG. 1.

FIG. 6 is a right side view of the case of FIG. 1.

FIG. 7 is a top view of the case of FIG. 1.

FIG. 8 is a bottom view of the case of FIG. 1.

FIG. 9 is an enlarged detail view of the encircled region of FIG. 1; and,

FIG. 10 is an enlarged detail view of the encircled region of FIG. 2.

The dot-dash broken line circles and lead lines extending therefrom in FIGS. 1 and 2 and the dot-dash broken line circles in FIGS. 9 and 10 delineate portions of the case for an electronic device, including claimed subject matter, that are shown on an enlarged scale in FIGS. 9 and 10. The other dot-dash broken lines in FIGS. 1 and 2 represent the bounds of the claimed design. The dashed broken lines throughout the drawing figures depict portions of the case for an electronic device that form no part of the claimed design. The dot-dash and dashed broken lines form no part of the claimed design.
